UNITED STATES PATENT OFFICE

HEINRICH KOPPERS, OF ESSEN, POSTFACH, GERMANY

BLAST FURNACE

Application filed September 29, 1922, Serial No. 592,022. Renewed March 1, 1927.

This invention relates to blast furnace construction and particularly to the construction of the upper part of the stack or shaft of such a furnace.

5 It is well known that the upper portions of blast furnace stacks require relatively frequent repair or renewal, owing to the rapid wearing away of the wall in that region. This excessive wearing of the upper portion 10 of the stack is chargeable to two mutually contributing factors, first, impact of incoming charges of ore, coke etc., against the wall and, second, weakening of that portion of the wall which receives the impact, by the wide 15 fluctuations of temperature which occur in that region of the furnace. Thus, a range of temperatures running from 250° F. to 900° F. is not unusual in the upper part of the furnace and fluctuations of such magnitude, 20 occurring sometimes very suddenly, subject the material of the wall to severe strains which weaken its resistance to the impact of incoming charges. The best fire-brick or 25 refractory lining thus far produced will crumble away, long before the remainder of the furnace has outlived its usefulness, owing to the breaking down of its cohesive strength under alternate expansion and contraction. It has been attempted to meet the difficulty 30 by protecting the impact surface with wear-plates of steel or iron; but these also suffer deterioration, buckling and shifting until they become loosened and fall down into the 35 charge.

The primary object of my invention is to provide an improved construction for the top of a blast furnace in order to lengthen the term of its usefulness and reduce the expense of repairs and replacements. A further 40 object attained by my improved construction is the maintenance of a somewhat more uniform temperature within the upper part of the stack.

In carrying out my invention, I eliminate 45 the customary brick lined wall at the top of the stack and substitute therefor a double walled steel cylinder or jacket in which a cooling medium, preferably water, is circulated. I am aware that it has been proposed 50 heretofore to equip blast furnaces with water

jackets for various purposes but so far as I know there has been suggested no successful solution of the problem herein dealt with. With the above mentioned objects in view, my invention resides in certain novel structural features of the water jacket and in the water circulating system. 55

In the accompanying drawings I have illustrated a constructional embodiment of my invention, Fig. 1 being a vertical central sectional view of a blast furnace equipped with my improvements, and Fig. 2 a partial view in elevation of the same on a larger scale. 60

As shown in the drawings, the hearth and bosh portions of the furnace, and part of the 65 stack, are of usual construction, comprising a metallic shell 4 and a refractory lining 2, both apertured for insertion of tuyers 6. At the top is the usual charging bell provided with valves 8 and 10. It is thought that further description of the parts thus far mentioned is unnecessary as my invention is not concerned with them and they may be of any 70 approved construction.

The refractory lining 2 is not carried to the 75 top of the stack but terminates below the level where it would be bombarded by incoming ore and coke; and below the region wherein the greatest fluctuations of temperature occur. These temperature fluctuations, ranging from 250° F. or even lower, to 900° F. or above are caused, on the one hand, by an abnormal passage of hot gases through relatively pervious parts of the charge, and on 80 the other hand, by incoming charges of cold ore, coke, etc. The region of greatest temperature fluctuations is in the neighborhood of the top of the charge, which does not remain at a constant level, but moves up or down, a distance of several feet, as a fresh 85 charge is introduced or molten pig iron is drawn off, respectively. In my judgment, an interval of 12 to 14 feet between the upper rim of the refractory lining and the charging bell will be an ample allowance for variations 90 in the height of the charge.

Between the charging bell and the top of shell 4 and lining 2 I interpose my improved top section of stack comprising a double walled cylinder having an outer wall 12 and 100

an inner wall 11, preferably of steel, and forming a water circulating annular chamber 14. The inner wall 11, is preferably corrugated, as shown, to strengthen it against the bombardment of incoming ore, etc.

In order to compensate for unequal vertical expansion of the inner and outer surfaces of lining 2, of the shell 4 relative to the lining, and of the inner and outer walls 11, 12, I provide a novel expansion joint comprising a flange 30, integral with or rigidly secured to the rim of shell 4, and a flange 31 similarly united to cylinder 12. As shown, flanges 30 and 31 are angularly disposed to one another, contacting at their outer edges and diverging inwardly to leave a space, which is filled with a compressible packing 32, of asbestos or the like. When cold, the joint will be as shown; when the furnace is being operated, the inner surface of lining 2 and inner wall 11 of the cylinder will expand more than shell 4 and wall 12, thus closing the gap between flanges 30 and 31.

Referring now to the water circulating system, this comprises a drum reservoir 20 and pipes 16 and 18, connecting the drum to the bottom and top respectively of the annular chamber 14. The reservoir 20 is provided with a water-supply pipe 22 having a valve 24; and a blow-off 26 of any suitable construction. Circulation of the water will be continuously effected by gravity, the hotter water rising in the chamber 14 and through the pipe 18, while the cooler water will descend through pipe 16. It is contemplated that the temperature of the water shall be maintained close to the boiling point. Any steam generated in chamber 14 will be partially condensed in drum 20, the excess passing out through blow-off 26. Sufficient water is admitted from time to time to supply the loss. By maintaining the water near the boiling temperature, in an arrangement such as described, a maximum cooling effect is obtained with a minimum consumption of water, and more important, the rapidity with which heat will be absorbed from the furnace is greatly enhanced. On the one hand, a sudden rise in temperature of the furnace wall will cause evolution of steam in the chamber 14 and the latent heat of vaporization will be taken mainly from the furnace wall. On the other hand, chamber 14 being unobstructed from top to bottom and annularly, the water can circulate rapidly and promptly reach the point of highest temperature in ample quantities. Any steam generated will rise freely to the top of chamber 14 and pass off through pipe 18 without trapping and carrying off a large quantity of water.

In addition to serving as a cooling device, my improved top section tends also to resist change of temperature downward, as when a fresh charge of cold ore and coke is introduced. When this occurs a transfer of heat

will take place, from the hot water in chamber 14 to the fresh charge. The amount of heat transferred will be drawn from all parts of the water system and also from the interior of the furnace adjacent the lower part of the chamber 14, at which level the charge is hot.

I claim:

1. In a blast furnace having an inner lining of refractory material thereon, a top shaft section comprising a double-walled metallic cylinder in combination with means for supplying a cooling medium thereto and an expansion joint between said top shaft section and the upper end of said lining of refractory material.

2. In a blast furnace having the lower portion of its wall formed of refractory material, a top shaft section forming the charging inlet to said furnace and contiguous to the chamber therein and comprising concentric metallic cylinders forming an annular water jacket unobstructed from top to bottom and annularly, in combination with means for maintaining water in said jacket under pressure to raise its boiling point and means for effecting thermosyphonic circulation of hot water between said means and said jacket.

3. In a blast furnace having the lower portion of its wall formed of refractory material, a top shaft section forming the charging inlet to said furnace and contiguous to the chamber therein and comprising concentric metallic cylinders forming an annular chamber unobstructed from top to bottom and annularly, in combination with a reservoir disposed at an elevation above the annular chamber, independent connections from below the water level in said reservoir to the top and to the bottom of said chamber, and a blow off for the reservoir.

4. In a blast furnace, a top shaft section forming the charging inlet to said furnace and comprising concentric metallic cylinders forming an annular chamber unobstructed from top to bottom and annularly the inner metallic cylinder being contiguous to the blast furnace chamber therein and being corrugated to strengthen such wall to resist shocks from ore and coke striking thereagainst during charging operations so that said wall may be made thin for rapid transfer of heat to water in said concentric cylinders notwithstanding the shocks and stresses to which it is subjected during charging operations, in combination with means for supplying a cooling medium to said chamber.

The foregoing specification signed at Cologne, Germany, this 10th day of August, 1922.

HEINRICH KOPPERS.
